ESCUTCHEON PLATE

Martin R. Lambertz, New Hamburg, Ontario, Canada,
assignor to Amerock Corporation, Rockford, Ill.

Continuation-in-part of design application Ser. No. 17,346,
May 26, 1969. This application May 25, 1970, Ser.
No. 23,119

Term of patent 14 years

Int. Cl. D8—09

U.S. Cl. D8—179

—FIG. 2.

—FIG. 5.

—FIG. 6.

FIG. 7.

FIG. 8.

FIG. 9.

FIG. 10.

FIG. 12.

FIG. 11.

FIG. 17.

FIG. 18.

FIG. 22.

FIG. 19.

FIG. 20.

FIG. 21.

FIG. 23.

FIG. 1 is a front view of an escutcheon plate incorporating my new design.

FIG. 2 is a side view as seen from the right of FIG. 1.

FIG. 3 is a back view of the plate.

FIG. 4 is an enlarged sectional view taken along the line 4—4 in FIG. 1.

FIG. 5 is an enlarged sectional view taken along the line 5—5 in FIG. 1.

FIG. 6 is an enlarged sectional view taken along the line 6—6 in FIG. 1.

FIG. 7 is a front view of a modified form of an escutcheon plate for a doorknob, the side view and the arcuate section being the same as shown in FIGS. 2 and 6, respectively.

FIG. 8 is an enlarged fragmentary sectional view taken along the line 8—8 in FIG. 7.

FIG. 9 is an enlarged fragmentary sectional view taken along the line 9—9 in FIG. 7.

FIG. 10 is a sectional view taken along the diameter of another modified form of an escutcheon plate for a doorknob, the side view and the arcuate section being the same as shown in FIGS. 2 and 6, respectively.

FIG. 11 is a reduced front view of the escutcheon plate shown in FIG. 10, the pattern being repeated around the entire periphery of the plate.

FIG. 12 is an enlarged fragmentary sectional view taken along the line 12—12 in FIG. 11.

FIG. 13 is a side view of another modified form of an escutcheon plate for a hook, the arcuate section being the same as shown in FIG. 6.

FIG. 14 is a front view of the escutcheon plate shown in FIG. 13.

FIG. 15 is an enlarged sectional view taken along the line 15—15 in FIG. 14.

FIG. 16 is an enlarged fragmentary sectional view taken along the line 16—16 in FIG. 14.

FIG. 17 is a front view of another modified form of an escutcheon plate for a door knob, that pattern being re-

peated around the entire periphery and the arcuate section being the same as shown in FIG. 6.

FIG. 18 is a side view of the escutcheon plate as seen from the right of FIG. 17.

FIG. 19 is an enlarged sectional view taken along the line 19—19 in FIG. 17.

FIG. 20 is an enlarged sectional view taken along the line 20—20 in FIG. 17.

FIG. 21 is an enlarged sectional view taken along the line 21—21 in FIG. 17.

FIG. 22 is a front view of another modified form of an escutcheon plate for a doorknob, the design being repeated around the periphery and the sections being the same as shown in FIGS. 19, 20 and 21.

FIG. 23 is a side view of the escutcheon plate as seen from the bottom of FIG. 22.

The portions shown in broken lines are for purposes of illustration only.

This application is a continuation-in-part of my co-pending application Ser. No. D. 17,346, filed May 26, 1969 and now abandoned.

I claim:

The ornamental design for an escutcheon plate, as shown and described.
